DESIGN FOR A BUCKLE

Pearl F. Ashton, Providence, R. I.

Application October 14, 1936, Serial No. 65,294

Term of patent 3½ years

To all whom it may concern:

Be it known that I, Pearl F. Ashton, a citizen of the United States of America, residing in 15 Belair Ave., Providence, county of Providence, and State of Rhode Island have invented a new, original, and ornamental Design for a Buckle, of which the following is a specification, reference being had to the accompanying drawing, forming part thereof,

Fig. 1 is a front view of a buckle showing my new design.

Fig. 2 is a plan view of a buckle as shown in Fig. 1.

I claim:

The ornamental design for a buckle substantially as shown.

PEARL F. ASHTON.
